TYPOGRAPHICAL CASTING MACHINE

Gustave Rapprich, West New York, N. J., assignor
to Mergenthaler Linotype Company, a corpora-
tion of New York

Application February 25, 1932, Serial No. 595,016

50 Claims. (Cl. 199—47)

This invention relates to slug casting machines, such as linotype machines of the general organization represented in United States Letters Patent No. 436,532 to O. Mergenthaler, wherein cir-

culating matrices are released from a magazine in the order in which their characters are to appear in print, and then composed in line together with spacers, the composed line transferred to the face of a mold, the mold filled with molten metal to form a slug or linotype against the matrices which produce the type characters thereon, and the matrices and spacers thereafter returned through distributing mechanism to the magazines from which they started. More par-

15 ticularly, it relates to certain improvements which adapt these machines, when so desired, to cast successively and automatically a plurality of duplicate slugs from each composed line.

In the preferred embodiment illustrated (al-

20 though it is not essential), the improvements have been worked out in the nature of an attachment which can be applied to almost any of the commercial machines with little or no alteration. Specifically, the equipment consists

25 of a star wheel adapted to be rotated periodically by the movement of the pump actuating lever (means being provided for connecting and disconnecting the star wheel to and from the pump lever to render the attachment operative or in-

30 operative as desired), and two main trains of connections leading therefrom and actuated thereby, one of which trains renders the auto-

35 matic clutch control dog operative and inoperative during alternate cycles of operation of the machine, and the other of which trains prevents the removal of the composed line from the first elevator until the last duplicate slug has been cast therefrom, and also prevents the delivery to the first elevator of a second composed line until

40 the first line has been removed therefrom.

The invention also contemplates an improved galley, which is divided into a plurality of compartments adapted to receive and hold the duplicate slugs in separate columns; and associated

45 with the galley is a guide controlled by the first elevator to direct the slugs into their proper compartments.

The exact construction and mode of operation of the parts will be best understood from the

50 detailed description to follow.

In the accompanying drawings, the invention is shown merely by way of example and in preferred form, but obviously many variations and modifications may be made therein which will

55 still be comprised within its spirit. It is to be

understood, therefore, that the invention is not limited to any specific form or embodiment, except insofar as such limitations are specified in the appended claims.

Referring to the drawings:

Fig. 1 is a front view of a portion of a linotype machine equipped with the improvements, showing the line delivery lock, the transfer slide lock, and the first elevator stop in active position, and showing also the improved galley (partly broken away) and the slug guiding mechanism associated therewith;

Fig. 2 is a side view of a section of the machine, showing the recasting equipment in side elevation;

Fig. 3 is a front sectional view of the machine, showing the recasting equipment in front elevation;

Fig. 4 is a front sectional view of the clutch control dog trip and the means controlled by the metal pump for actuating the trip to render the dog inoperative;

Fig. 6 is a perspective view of that portion of the recasting equipment showing the line transporter stop and the line delivery and line transfer for locks;

Fig. 7 is a vertical section taken through the star wheel and its actuating devices; and

Fig. 8 is a perspective view of the improved galley and slug delivery guide.

Referring to Fig. 1, when the machine is em-

ployed in the customary manner, that is to say,

90 to produce a single slug from each composed line, the matrices are released from their storage

magazine (not shown) and the spacers from their storage magazine A by a keyboard mechanism (not shown), and are delivered to and composed

95 in line in the assembler B. The assembler is then

manually elevated to raise the composed line be-

tween the fingers c and c¹ of the line delivery

100 slide C, which thereupon transfers the line from

the assembler through the intermediate channel D to the line transporter or first elevator E. The

105 first elevator E then descends to carry the line to the casting mechanism where it is justified and

then presented to the face of a mold into which molten metal is injected by means of a pump plunger F to cast a slug against the justified line, after which the slug is trimmed and delivered to the galley R. The first elevator ascends to its up-

110 most position and the line is shifted therefrom by the slide G into the upper transfer channel G¹, from which the spacers are returned to their mag-

azine A and the matrices raised by the second elevator G² and delivered to the distributing mechanism, whereby they are restored to their proper channels in the magazine from which they 5 started.

As is well understood in the art, the various parts referred to, with the exception of the assembler B which is under manual control, are operated from the main shaft of the machine, 10 which is caused to make one complete rotation at each cycle of operation. The shaft is driven by an electric motor through a spring-actuated clutch, this clutch being thrown into action by a trip dog J carried by a cam J¹ which is fast to 15 the main shaft. When the parts are at rest, the dog J engages and depresses a stop lever J², which when depressed acts through the usual connections to disengage the clutch. When, however, the dog J is moved laterally to clear the stop 20 lever J², as is done when the line delivery slide C is released, the clutch actuating spring is allowed to engage the clutch and thus start the operation of the machine. The trip dog J is also under manual control, there being employed for this 25 purpose, a train of connections leading to the front of the machine and which comprises in part a vertical sleeve J³, mounted to turn upon a fixed rod J⁴, and which is provided near its upper end with a radially extending arm J⁵ arranged 30 in position to engage the trip dog. By this arrangement, when the sleeve J³ is manually rotated, the arm J⁵ is caused to move the trip dog J clear of the stop lever J² so that the clutch may be engaged in the manner above stated. The 35 details of the clutch control mechanism are fully shown and described in the Rogers Patent No. 661,386, and being so well known they do not require any further description here.

To complete the identification of the known 40 parts, it may be added that the main shaft is also provided with a cam F¹ (see Fig. 5) which is shaped to control the operation of the pump plunger F during each machine cycle, this cam being arranged to act upon a pivoted lever F² 45 connected to the pump plunger, and which is connected in turn to the second longer lever F³ which is constantly urged downward to effect the pumping stroke by an attached spring F⁴. In this way, and as also well known, the pump plunger is 50 given one reciprocation at each cycle of operation of the machine, its down stroke, as effected by the spring F⁴, forcing metal into the mold for the casting of the slug, and its upward stroke, as effected by the cam F¹, being its return or inactive 55 stroke.

The parts so far described, and their normal mode of operation in casting single slugs, in themselves constitute no part of the present invention, 60 and are or may be of any suitable construction, such for instance as disclosed in the previously-mentioned Letters Patent No. 436,532, or as presented in the commercial linotype machine.

As already stated, the improved equipment is 65 intended to adapt the machine automatically to cast duplicate slugs from each of the composed lines when desired, to this end, there are employed means, which may be called into action at will for actuation by the operation of the metal pump 70 plunger F, whereby the transfer slide G is permitted to operate only at alternate ascents of the first elevator E, the line delivery slide C is prevented from transferring a new line to the first elevator until the preceding line has been 75 removed therefrom, and the clutch control dog J is

rendered inoperative so as to prevent the machine from stopping at the end of the first cycle of operation, thereby permitting the composed line to be returned a second time to the casting mechanism.

Reference will be made first to the means employed for controlling the operation of the transfer slide G. As shown in several of the figures, the transfer slide G is normally locked against operation by a latch O, which is pivoted to the machine frame as at O¹, and which is provided with a nose or shoulder O² arranged in engagement with a pin O³ projecting forwardly from the transfer slide. At one side of the pivot O¹, the latch O is provided with a forward projecting pin O⁴, which is arranged in position to be engaged by the head of the first elevator E in its upward movement. If the first elevator E makes a full ascent in rising to its line removing position, it engages the projecting pin O⁴ and lifts the latch O clear of the pin O³, so as to permit the transfer slide to remove the composed line from the first elevator, as intended. If, however, the first elevator fails to rise to its full extent, it will fail to engage the pin O⁴ or to lift the latch O clear of the pin O³, and thereby leave the transfer slide locked against operation so that it cannot remove the composed line from the first elevator.

According to the invention, means are provided for controlling the extent of the upward movement of the first elevator E, these means, as will later be described, being actuated by the operation of the metal pump plunger F, so as at one operation of the machine to prevent the full ascent of the first elevator, and so as at the next operation of the machine to permit the full ascent of the first elevator, it being in this way that the removal of the line is prevented and permitted at alternate operations of the machine.

The means referred to, in the embodiment herein illustrated, comprise a stop piece P attached to the lower end of the forward arm of a U-shaped bail P¹, pivoted at P² to an upstanding support P³ mounted on the machine frame. Consequently, when the bail P¹ is rocked upwardly, the stop P will be located in an inactive position or out of engaging relation to the first elevator which, therefore, will be allowed to make a full ascent (see Fig. 3); whereas, when the bail P¹ is moved downwardly, it will locate the stop piece P in its active position or in engaging relation to the first elevator E so as to arrest the latter in its upward movement and thereby prevent its complete ascent (see Fig. 1). The operating connections for the bail P will be described at a later point.

Reference will next be made to the means provided for locking the line delivery slide C against movement. As shown in Figs. 1, 2, and 6, these means comprise essentially a long locking lever T, which is arranged in the guideway wherein the line delivery slide C is mounted to reciprocate. The lever T, at its extreme left, is made fast to a shaft T¹, journaled in a supporting block T² attached to the machine frame, and at its rear end the shaft T¹ is provided with a depending twisted arm T³, which is connected to the pump plunger F by a system of levers later to be described. Normally, the locking lever T will occupy its inactive position as shown in Fig. 2, where it will be seen that the free end of the lever is held, against the pressure of a leaf spring T⁴, below or out of the path of move- 150

ment of the line delivery slide C, thus permitting the transfer of the composed line from the assembler B to the first elevator E. Such is the relation of the parts when a composed line is

5 forwarded for the first casting operation. After this first casting operation, however, and due to the operation of the pump plunger F, the locking lever T is moved to its active position, as shown in Fig. 1, where it will be seen that
10 the free end of the lever is adapted to engage the block C¹ of the line delivery carriage and thereby prevent the movement of the carriage to the left for the transfer of a newly composed line to the first elevator for the second slug
15 casting operation. It is only after this second slug casting operation has been effected that the locking lever T, by the second actuation of the pump plunger F, is moved out of the way to permit the transfer of the newly composed line
20 to the first elevator.

Reference is now made to the means provided for causing the machine to carry out the second casting operation automatically. In the present instance, and as best shown in Figs. 3, 4, and 5, 25 there is associated with the actuating arm J⁵ for the trip dog J, a rightangularly disposed cam H made fast to the rear end of a shaft H² journaled in the depending arm of a supporting bracket H³, the latter being attached fixedly to the supporting 30 rod J⁴ on which the arm carrying sleeve J³ is mounted to turn. Normally, the high point H¹ of the cam H occupies the inactive position shown in Fig. 3, i. e. out of engagement with the arm J⁵, but when the cam is rotated clockwise, its high point H¹ is brought into engagement with the arm J⁵ and the latter is rocked toward the left to move the trip dog J clear of the stop lever J² so as to bring about the engagement of the main clutch. The cam H is moved to this active position by the 35 operation of the pump plunger F in carrying out the first slug casting operation, and hence when the trip dog J is carried around to its starting position by the rotation of the main shaft, the arm J⁵ will prevent it from engaging the stop lever J² and thus leave the clutch engaged to cause a 40 second rotation of the main shaft and consequently a second casting operation. The operation of the pump plunger F in performing the second casting operation, however, will move the cam H counterclockwise to its inactive position as shown in Fig. 3, so that on this occasion, when the stop dog J is brought again to its starting position, it will be allowed to engage and depress the stop lever J² and thereby disengage the clutch to 45 arrest the machine as normally.

50 The connections from the pump plunger F to the several parts which are operated therefrom will now be described. As best shown in Figs. 2 and 5, there is located in the immediate vicinity of the pump plunger F a four-arm star wheel S, which has fast thereto an eight-tooth ratchet disc S¹. The star wheel, with its ratchet, is rotatably mounted upon an enlarged hub portion S² of a rod or bolt S³, attached to a supporting plate L mounted upon the machine frame. The rod or bolt S³ is extended to the left, as clearly shown in Fig. 7, and has rotatably mounted thereon a toothed actuating disc S⁴ for engagement with the ratchet S¹. A compression spring S⁵, also carried 55 by the bolt S³, acts constantly to maintain the actuating disc S⁴ in engagement with the ratchet S¹, but will permit the actuating disc to yield laterally upon the bolt S³ when turned in a counterclockwise direction on its inactive stroke. The 60 turning of the disc S⁴ in a clockwise direction,
70

which is its active stroke, will advance the ratchet S¹ one tooth forward and impart a similar rotation to the star wheel S. Briefly stated, the arrangement is such that, at each operation of the toothed disc S⁴, the ratchet S¹ will be advanced 80 one-eighth of a rotation and thereby advance the star wheel S one-eighth of a rotation, the latter acting at successive advances through two trains of connections alternately to render the line removing means, the line delivering means and the 85 machine stopping means inoperative and operative, respectively, whereby the machine will operate automatically to cast duplicate slugs from the consecutive composed lines.

The ratchet S¹ is connected to the pump lever F² by means of a U-shaped bail F⁵, one end of which is secured to the lever F³ by a clamp connection F⁶. The other end of the bail F⁵, adjacent the star wheel S, is formed with a hollow boss F⁷, in which there is provided a manually retractable 90 spring detent F⁸, which serves as a means for connecting and disconnecting the bail F⁵ to and from the actuating disc S⁴, the latter being provided with an operating arm S⁷ adapted to be engaged by the detent F⁸ and which is formed with 95 a slot or opening S⁶ to permit a certain amount of lost motion.

The star wheel S, which controls the setting of the first elevator stop P, the line delivery slide stop T, and the clutch control dog disengaging 105 cam H, is connected with these three elements through two main trains of connections as already stated.

The connections between the star wheel S and the cam H consist of a lever H⁸ pivotally mounted 110 on the bracket L, a right angularly disposed bell-crank lever H⁴ mounted on a shaft H³ journaled in the bracket H³, and a link H⁵ which connects these two levers. The lever H⁸ is provided at its free end with a roller H⁶, adapted to ride on the 115 periphery of the star wheel S, and which is held in engagement therewith by a spring H⁷ pulling upwardly on the lever H⁸. The lever H⁴, at its free end, is forked or bifurcated and engages with a pin H¹⁰ projecting forwardly from the side of 120 the cam H. By this arrangement, at successive advances of the star wheel, the roller H⁶ rides into a depression s between adjacent arms of the star wheel and then up onto the peak s¹ of an arm of the star wheel, causing the levers H⁸ and H⁴ 125 to rock about their pivots and to rotate the cam H alternately in opposite directions, whereby the clutch control dog J is governed in the manner before described.

The other train of connections consists of a 130 lever M, pivotally mounted on a forwardly extending arm L¹ of the bracket L, and a right angularly disposed bell-crank lever M¹ pivotally mounted on an angular extension L² of the bracket arm L¹. The lever M is provided at its 135 free end with a roller M⁴ adapted to ride on the periphery of the star wheel S in the same manner as the roller H⁶ of the lever H⁸, it being held in engagement therewith by a spring M⁵ connected to one arm of the bell-crank M¹ and to the extension L² of the bracket L. At one end, the bell-crank lever M¹ is forked or bifurcated (like the lever H⁴) and engages the end of the lever M¹ (see Fig. 3), a certain amount of play thus being allowed between these levers in operation. Connected to the other end of the bell-crank lever M¹ are two rods M² and M³, which connect it with the bail P¹ carrying the first elevator stop piece P, and the arm T³ of the line delivery stop lever T, respectively, the arrangement being such that 140 145 150

as the levers M and M¹ are rocked about their pivots during the rotation of the star wheel S, the stops P and T are both moved into and out of active position alternately in the manner before described.

Referring now to the improved galley, it is provided with a plurality of compartments for holding the slugs in separate columns, in order that the duplicate slugs may be kept apart and thus 10 obviate the necessity of sorting them out by hand later on. In the present embodiment, and referring particularly to Fig. 8, the inclined galley R is divided into upper and lower compartments R¹ and R², respectively, into which the slugs are 15 selectively delivered as they are ejected from the mold and in which they are progressively advanced by a stacking device R³. The inclined chute N, down which the ejected slugs pass to the galley, is provided with a guide N¹, fastened 20 to the machine by a suitable hinge n, which forms the right-hand side wall of the chute and which extends forwardly, as at N², into the galley R. Another guide N³ is pivotally attached to the lower end of the left-hand side wall of the chute, 25 and is connected to and spaced apart from the guide N¹ by a bent link or rod N⁴, whereby the swinging of one guide about its pivot will bring about a corresponding movement of the other.

The connecting link N⁴ is rigidly secured to the 30 left-hand guide N³ but has a sliding engagement with the right-hand guide N¹, being disposed between the outer face of the right-hand guide and a bracket N⁵ secured thereto, thus enabling the two guides to partake of a differential swinging 35 movement resulting from the difference in location of their respective pivots. At this point it may be well to note that the differential movement is utilized to contract the space between the two guides when they are adjusted to direct the 40 slugs into the lower compartment R², the shorter guide N³ being caused to approach the longer guide N¹ and thus act to deflect the slugs, as they pass between the guides, toward the right and away from the end of the upper flange or shelf R⁶.

45 In order that the guides may normally be held in a position to direct the slugs into the upper compartment R¹, the bracket N⁵ is provided with a depending portion N⁶, adapted to be held between the galley supporting bracket R⁴ and a raised 50 rib N⁷ formed on a resilient member N⁸ secured to the bracket R⁴, the engagement, however, being such that very little force is necessary to move the member N⁶ over the rib N⁷ when the guide plates N¹ and N³ are swung from one position to 55 another.

The operation of the chute guides N¹ and N³ is effected by a plunger V, which passes beneath the guides and which is provided at one end with an upright pin V¹, arranged to project through a 60 ringlet N⁹ secured to the bracket N⁶ on the outer face of the guide N¹. The other end of the plunger V is in the form of a cam V², adapted to be engaged by a roller V³ journaled in the bifurcated end of an extended bolt V⁴, which replaces the 65 bolt ordinarily used to secure the upper end of the link V⁵ connecting the first elevator E to its actuating lever. A pin or lug R⁵ projects from the head of the stacking device R³ and is arranged to engage the outer face of the lower end of the 70 guide N¹, so that when the guides are moved to the right to direct a slug into the lower compartment, the stacking device R³ is also carried to the right out of the path of the slug. This pin or lug R⁵ also serves as a means whereby the active 75 stroke of the stacking device R³ will return the

guides to their normal positions after the transporter E descends from line removing position and disengages the roller V³ from the plunger cam V².

In this connection, it is pointed out that when the first elevator E makes a complete ascent, the roller V³ engages the cam V² and pushes the plunger V to the right and with it the two connected guides N¹ and N³ as well as the stacking device R³. Under such conditions, the slugs will be delivered into the lower compartment R², being arrested by the lower flange or shelf R⁸. When, however, the first elevator is arrested in its upward movement by the stop P, the roller V³ fails to engage the cam V² and thus allows the guides N¹ and N³ to remain in their position to the left, to which they have, in the meantime, been returned by the active stroke of the stacking device R³. Under such conditions, the slugs will be delivered into the upper compartment R¹, being arrested by the upper flange or shelf R⁶ which extends far enough to the right to intercept the slugs at the time. The stacking device R³ is slotted at R⁷ to clear this upper flange or shelf R⁶.

In the operation of the machine, when it is 100 desired to cast duplicate slugs, the detent F⁸ is set to connect the star wheel S to the pump actuating lever F³. The first composed line is then delivered to the first elevator and the machine started in the ordinary manner. When 105 the pump actuating lever F³ is moved downwardly to inject molten metal into the mold for the casting of the first slug, the ratchet actuating disc S⁴ is moved in a counterclockwise direction in its idle stroke to pick up one tooth on the 110 ratchet S¹, and as the lever F³ is raised to its normal position by the rotating cam F¹ on the main shaft, the actuating disc S⁴ is turned in a clockwise direction one-eighth of a rotation, thereby advancing the star wheel S one-eighth 115 of a turn.

This fractional rotation of the star wheel S causes the rollers H⁶ and M⁴ of the levers H⁸ and M, respectively, to come to rest in the depressions s. Thereupon, the upward pull of the 120 spring H⁷ on the lever H⁸ causes the latter to rock about its pivot, exerting a downward pressure on the connecting link H⁵, whereby the bell-crank H⁴ is rocked about its pivot and the cam H rotated in a clockwise direction to bring its high 125 point H¹ into engagement with the clutch control trip dog actuating arm J⁵. At the same time, the movement of the roller M⁴ into its depression (the one opposite from that of the roller H⁶) permits the pull of the spring M⁵ to rock the bell-crank M¹ in a counterclockwise direction, thereby 130 exerting a downward pull on the rod M² to bring the elevator stop P into active position, and releasing the pressure of the rod M³ on the arm T³, so that the leaf spring T⁴ may act to raise the 135 locking lever T into active position in front of the block C¹ on the line delivery slide C.

As a result, the line delivery slide C is prevented (by the locking lever T) from delivering a new or second composed line to the first elevator 140 E, the first elevator is prevented (by the stop piece P) from making a full ascent into line removing position and consequently preventing the removal therefrom of the first composed line, and the actuating arm J⁵ is cammed into active position to trip the clutch control dog J at the end of the first cycle of operation and thereby cause the machine to continue through a second cycle of operation.

When the first composed line is presented a 145

second time to the mold, and the pump lever F^3 is actuated to inject molten metal thereinto for the casting of the duplicate slug, the ratchet actuating disc S^4 is again operated to advance the star wheel S through another one-eighth rotation to cause the rollers H^6 and M^4 to ride up onto the peaks s^1 of the star wheel arms. This further fractional rotation of the star wheel rocks the levers H^8 and M against the tension of their springs H^7 and M^5 in directions contrary to those above described, causing a counterclockwise rotation of the cam H to disengage its high point H^1 from the clutch control trip dog actuating arm J^5 , and a clockwise rotation of the bell-crank M^6 to 80 move the rod M^2 upwardly and carry the elevator stop piece P out of active position, and to move the other rod M^3 downwardly and swing the stop lever T downwardly against the pressure of the leaf spring T^4 out of the path of the line delivery slide C .

As a result of this alternate operation of the parts, the first elevator E is permitted to make a complete ascent for the removal of the first line therefrom, the line delivery carriage C is unlocked and permitted to transfer into the first elevator the second or newly composed line, and the trip dog J is unaffected by the cam H and allowed to stop the (being its second) operation of the machine.

30. The continued fractional rotations of the star wheel S puts the parts through the same operations as above described for the first line, it being understood that the machine will continue automatically to cast duplicate slugs from each successive line until the recasting attachment is rendered inoperative by manually retracting the spring detent F^8 .

The operation of the mechanism for delivering successively cast slugs to different compartments in the galley has already been sufficiently described.

In the course of the description, attention has been called to the fact that the improvements are in the form of an attachment which may readily be applied to existing machines, and the improvements have been described as such. In this connection, however, it is to be understood that the improvements may also be formed as a part of the machine without departing from the spirit of the invention.

Having thus described my invention, what I claim is:

1. In a slug casting machine, the combination of a transporter for presenting a composed line to the mold, an assembler wherein the line is composed, means for transferring the composed line from the assembler to the transporter, and automatic means for locking the line transfer means against action until the machine has completed several cycles of operation, said locking means acting directly on the transfer means and independently of the assembler.

2. In a slug casting machine, the combination of a transporter for presenting a composed line to the mold, an assembler wherein the line is composed, means for transferring the composed line from the assembler to the transporter, and automatic means acting alternately to lock and unlock the line transfer means at successive operations of the machine, said locking means acting directly on the transfer means and independently of the assembler.

3. In a slug casting machine, the combination of a pump for injecting molten metal into the mold, a transporter for presenting a composed

line to the mold, an assembler wherein the line is composed, means for transferring the composed line from the assembler to the transporter, and means actuated by the operation of the pump for locking the line transfer means against action until the machine has completed several cycles of operation.

4. In a slug casting machine, the combination of a pump for injecting molten metal into the mold, a transporter for presenting a composed line to the mold, an assembler wherein the line is composed, means for transferring the composed line from the assembler to the transporter, and means actuated by successive operations of the pump and acting alternately to lock and unlock the line transfer means.

5. In a slug casting machine, the combination of a pump for injecting molten metal into the mold, a transporter for presenting a composed line to the mold, an assembler wherein the line is composed, means for transferring the composed line from the assembler to the transporter, and means actuated by the operation of the pump for preventing the transfer of a line from the assembler until the machine has completed several cycles of operation.

6. In a slug casting machine, the combination of a pump for injecting molten metal into the mold, a transporter for presenting a composed line to the mold, an assembler wherein the line is composed, means for transferring the composed line from the assembler to the transporter, and means actuated by successive operations of the pump and acting alternately to prevent and permit the transfer of a line from the assembler.

7. In a slug casting machine, the combination of a pump for injecting molten metal into the mold, a vertically movable transporter for presenting a composed line to the mold, and means actuated by the operation of the pump for limiting the upward movement of the transporter after given casting operations.

8. In a slug casting machine, the combination of a pump for injecting molten metal into the mold, a vertically movable transporter for presenting a composed line to the mold, and means actuated by successive operations of the pump and acting alternately to prevent and permit full upward movement of the transporter.

9. In a slug casting machine, the combination of a pump for injecting molten metal into the mold, a transporter for presenting a composed line to the mold, means for removing the line from the transporter, and means actuated by the operation of the pump to prevent the removal of the line from the transporter until the machine has completed several cycles of operation.

10. In a slug casting machine, the combination of a pump for injecting molten metal into the mold, a transporter for presenting a composed line to the mold, means for removing the line from the transporter, and means actuated by successive operations of the pump and acting alternately to prevent and permit the removal of the line from the transporter.

11. In a slug casting machine, the combination of a pump for injecting molten metal into the mold, driving mechanism including a rotary wheel provided with a clutch controlling dog, and means actuated by the operation of the pump for preventing the action of said dog at successive rotations of the wheel.

12. In a slug casting machine, the combination of a pump for injecting molten metal into the

13. A combination according to claim 5 including as an additional element means for rendering the pump actuated means inactive at will. 80
14. In a slug casting machine, the combination 10 of a pump for injecting molten metal into the mold, a transporter for presenting a composed line to the mold, means for operating the transporter, and means actuated by the operation of the pump to cause the transporter to present 15 the line to the mold a plurality of times for casting. 85
15. In a slug casting machine, the combination 20 of a pump for injecting molten metal into the mold, a transporter for presenting a composed line to the mold, means for removing the line from the transporter after casting, and means actuated by the operation of the pump to prevent the removal of the line from the transporter and to cause the transporter to present the line 25 to the mold a plurality of times for casting. 90
16. In a slug casting machine, the combination 30 of a pump for injecting molten metal into the mold, a transporter for presenting a composed line to the mold, means for delivering the line 35 to the transporter, and means actuated by the operation of the pump to cause the transporter to present a delivered line to the mold a plurality of times for casting, and to prevent the delivery to the transporter of a second line until the several casting operations have been completed. 95
17. In a slug casting machine, the combination 40 of a pump for injecting molten metal into the mold, a transporter for presenting a composed line to the mold, means for delivering the line 45 to the transporter, means for removing the line from the transporter, and means actuated by the operation of the pump to cause the transporter to present a delivered line to the mold a plurality of times for casting, to prevent the removal of said line from the transporter until the several casting operations have been completed, and to prevent the delivery to the transporter of a second line until the first line has been removed. 100
18. A combination according to any one of the foregoing claims, characterized by the fact that the pump actuated means therein referred to include a rotary star wheel, a ratchet mechanism for rotating the star wheel step by step, an actuating member for the ratchet mechanism mounted on the pump operating lever, and connections operated by the star wheel in its rotation and leading to the part or parts which are controlled by the operation of the pump. 110
19. A combination according to any one of the foregoing claims, characterized by the fact that the pump actuated means therein referred to include a rotary star wheel, a ratchet mechanism for rotating the star wheel step by step, an actuating member for the ratchet mechanism mounted on the pump operating lever, and means for connecting and disconnecting the ratchet mechanism to and from said actuating member at will. 115
20. In a slug casting machine, the combination 60 of a transporter for presenting a composed line to the mold, means for preventing the removal of the line from the transporter, means for preventing the delivery of a new line to the transporter until the preceding line has been removed there- 120
- from, means for causing the transporter to present the line to the mold a plurality of times for casting, a single movable control element, and actuating connections between said element and all of said means, whereby the operation of the latter is controlled directly by the movement of said single element. 125
21. In a slug casting machine, the combination 130 of a transporter for presenting a composed line to the mold, means for preventing the removal of the line from the transporter, means for preventing the delivery of a new line to the transporter until the preceding line has been removed therefrom, means operative to cause the transporter to present the line to the mold a plurality of times for casting, a single control element operated periodically, and actuating connections between said element and all of said means, whereby the operation of the latter is controlled directly by the periodic operations of said 135 single element. 95
22. In a slug casting machine, the combination 140 of a pump for injecting molten metal into the mold, a transporter for presenting a composed line to the mold, means for preventing the removal of the line from the transporter, means for preventing the delivery of a new line to the transporter until the preceding line has been removed therefrom, means for causing the transporter to present the line to the mold a plurality of times for casting, and a single element periodically actuated by the operation of the metal pump for controlling the operation of all of said means. 100
23. In a slug casting machine, the combination 145 of a pump for injecting molten metal into the mold, a transporter for presenting a composed line to the mold, means for preventing the removal of the line from the transporter, means for preventing delivery of a new line to the transporter until the preceding line has been removed therefrom, means operative to cause the transporter to present a line to the mold a plurality of times for casting, and a single element adapted to be actuated by successive operations of the metal pump alternately to render all of said means operative and inoperative. 110
24. In a slug casting machine, the combination 150 of a transporter for presenting a composed line to the mold, means for preventing the removal of the line from the transporter, means for preventing the delivery of a new line to the transporter until the preceding line has been removed therefrom, means for causing the transporter to present the line to the mold a plurality of times for casting, and means for controlling the operation of all of said first-mentioned means, the controlling means being connected to one of said other means by one train of connections and to the remainder of said other means by another train of connections. 115
25. In a slug casting machine, the combination 155 of a transporter for presenting a composed line to the mold, means for preventing the removal of the line from the transporter, means for preventing the delivery of a new line to the transporter until the preceding line has been removed therefrom, means for causing the transporter to present the line to the mold a plurality of times for casting, and a single element for controlling the operation of all of said first-mentioned means, the controlling element being connected by one train of connections to the means for preventing the removal of the line from the transporter and the means for pre- 160

venting the delivery of a new line to the transporter, and being connected by another train of connections to the means for causing the transporter to present the line to the mold a plurality of times for casting.

26. In a slug casting machine, the combination of a pump for injecting molten metal into the mold, a transporter for presenting a composed line to the mold, a slide for delivering the line to the transporter, a stop for locking said slide against movement, and means actuated by successive operations of the pump to render the delivery slide stop alternately operative and inoperative.

10 27. In a slug casting machine, the combination of a pump for injecting molten metal into the mold, a transporter for presenting a composed line to the mold, a slide for delivering the line to the transporter, a stop for locking said slide against movement, and a star wheel adapted to be rotated step by step by a ratchet mechanism actuated by the pump operating lever, said star wheel operating through a train of connections alternately to render the delivery slide stop operative and inoperative.

20 28. In a slug casting machine, the combination of a pump for injecting molten metal into the mold, a vertically movable transporter for presenting a composed line to the mold, a stop adapted to be moved into position to limit the upward movement of the transporter after given casting operations, and means actuated by the operation of the pump to move said stop into active position.

30 29. In a slug casting machine, the combination of a pump for injecting molten metal into the mold, a vertically movable transporter for presenting a composed line to the mold, a movable stop for limiting the upward movement of the transporter, and means actuated by successive operations of the pump and acting alternately to move said stop into and out of active position.

35 30. In a slug casting machine, the combination of a pump for injecting molten metal into the mold, a transporter for presenting a composed line to the mold, a stop adapted to be moved into and out of active position to limit the upward movement of the transporter after successive casting operations, and a star wheel associated with said stop by a train of connections and adapted to be rotated step by step by successive operations of the pump alternately to move said stop into active and inactive position.

45 31. In a slug casting machine, the combination of a pump for injecting molten metal into a mold, driving mechanism including a rotary wheel provided with a clutch controlling dog, a trip for releasing said dog, a cam for actuating said trip, and means associated with said cam and adapted to be actuated by the operation of the pump to move the cam into engagement with said trip, whereby the latter is moved into position to prevent the action of said dog at successive rotations of the wheel.

50 32. In a slug casting machine, the combination of a pump for injecting molten metal into the mold, driving mechanism including a rotary wheel provided with a clutch controlling dog, a trip for releasing said dog, a cam for actuating said trip, and a star wheel associated with said cam and adapted to be periodically advanced by the operation of the pump alternately to move the cam into and out of engagement with the trip,

whereby the latter is rendered inoperative and operative at successive operations of the machine.

33. In a slug casting machine, the combination of a casting mechanism, an inclined galley for receiving the slugs and being adapted to hold them in a plurality of columns therein, and guide means associated with the galley and movable laterally to direct successively cast slugs into different columns.

10 34. In a slug casting machine, the combination of a movable transporter for presenting a composed line to the mold, an inclined galley for receiving the slugs and being adapted to hold them in a plurality of columns therein, and guide means associated with the galley and movable laterally to direct successively cast slugs into different columns, said guide means acting on each successive slug and being controlled by the movement of the line transporter.

20 35. In a slug casting machine, the combination of a casting mechanism for casting duplicate slugs from successive composed lines, an inclined galley for receiving the slugs and being divided into upper and lower compartments, and automatically operated guide means associated with the galley and movable laterally alternately to direct the duplicate slugs into the different compartments, said guide means acting to support and direct each slug delivered to the galley to its intended compartment.

30 36. In a slug casting machine, the combination of a casting mechanism, an inclined galley for receiving the slugs and being divided into upper and lower compartments for holding the slugs in separate columns, a chute for conveying the slugs to the galley, and a guide pivotally attached to said chute and movable laterally to direct successively cast slugs into the different compartments.

40 37. In a slug casting machine, the combination of a vertically movable transporter for presenting a composed line to the mold, an inclined galley for receiving the slugs and being divided into upper and lower compartments for holding the slugs in separate columns, a chute for conveying the slugs to the galley, and a pair of guides pivotally attached to the chute and movable laterally automatically for directing successively cast slugs alternately into one compartment or the other of the galley.

50 38. In a slug casting machine, the combination of a vertically movable transporter for presenting a composed line to the mold, an inclined galley for receiving the slugs and being divided into upper and lower compartments for holding the slugs in separate columns, a chute for conveying the slugs to the galley, and a pair of guides pivotally attached to the chute and connected together for movement as a unit to direct the slugs into one compartment or the other of the galley.

60 39. A combination as in claim 38, wherein the guide plates are provided with an actuating member adapted to be engaged by a cooperating member on the transporter and located thereon so as to engage said cam surface only when the transporter makes a full ascent.

70 40. In a slug casting machine, the combination of a vertically movable transporter for presenting a composed line to the mold, an inclined galley for receiving the slugs and being adapted to hold them in a plurality of columns therein, guide means associated with the galley and movable laterally to direct successively cast slugs into different columns, said guide means being movable in one direction by the transporter, and

means for moving the guide means in the other direction.

41. In a slug casting machine, the combination of a vertically movable transporter for presenting a composed line to the mold, an inclined galley for receiving the slugs and being adapted to hold them in a plurality of columns therein, a stacking device for advancing the slugs in the galley, and guide means associated with the galley and movable laterally to direct successively cast slugs into different columns, said guide means being moved in one direction by the operation of the transporter and in the other direction by the operation of the stacking device.

42. In a slug casting machine, the combination of a pump for injecting molten metal into the mold, a vertically movable transporter for presenting a composed line to the mold, means actuated by the operation of the pump for controlling the movement of the transporter after given casting operations, an inclined galley adapted to hold the slugs in a plurality of columns, and guide means associated with the galley and movable laterally to direct successively cast slugs into different columns, the movement of the guide means being dependent upon the movement of the transporter.

43. In a slug casting machine, the combination of a pump for injecting molten metal into the mold, a vertically movable transporter for presenting a composed line to the mold, means actuated by the operation of the pump and adapted to be moved into active and inactive position so as to prevent and permit the movement of the transporter into line removing position so that a plurality of slugs may be cast from successive composed lines, an inclined galley for receiving the slugs and adapted to hold them in different columns, and guide means associated with the galley and being movable laterally by the transporter to direct the slugs into the different columns, the movement of the guide means by the transporter being dependent upon the different movements of the latter.

44. In a slug casting machine, the combination of a pump for injecting molten metal into the mold, a vertically movable transporter for presenting a composed line to the mold, means actuated by the operation of the pump and mova-

ble into and out of position alternately to prevent and permit the movement of the transporter into line removing position so that duplicate slugs may be cast from successive composed lines, an inclined galley adapted to hold the slugs and being divided into upper and lower compartments, and guide means associated with the galley and movable laterally to direct successively cast slugs into one or another of the compartments, the movement of the guide means being effected by the movement of the transporter into line removing position.

45. A combination as set forth in claim 44, characterized by the fact that the guide means and the transporter are provided with cooperating elements adapted to engage and effect a movement of the former when the latter makes a full ascent into line removing position.

46. A combination as set forth in claim 41, wherein the stacking device and guide means are connected so that the movement of the latter by the transporter will move the stacking device out of the path of the slug to be delivered.

47. A combination as set forth in claim 41, wherein the stacking device and guide means are connected so that the movement of the latter by the transporter will move the stacking device out of the path of the slug to be delivered, and so that the active stroke of the stacking device will return the guide means to its normal position.

48. A combination as set forth in claim 41, characterized by the fact that the guide means and the transporter are provided with cooperating elements adapted to engage and effect a movement of the former from its normal position when the latter moves to line removing position, and further characterized by the fact that the stacking device and guide means are provided with engaging means whereby the former is moved out of the path of the slug to be delivered and upon its active stroke returns the guide means to its normal position.

49. A combination according to claim 9, including as an additional element means for rendering the pump-actuated means inactive at will.

50. A combination according to claim 11, including as an additional element means for rendering the pump-actuated means inactive at will.
